United States Patent Office

Des. 193,624
Patented Sept. 18, 1962

193,624

CHILD'S VEHICLE

Herbert E. Wolner, Mound, Minn.

Filed Dec. 22, 1960, Ser. No. 63,304

Term of patent 3½ years

(Cl. D34—15)

FIG. 1

FIG. 2.

The side portion not shown is substantially plain.

I claim:

The ornamental design for a child's vehicle, as shown and described.
